UNITED STATES PATENT OFFICE.

FELIX MUELLER, OF NEW YORK, N. Y., ASSIGNOR TO STANDARD STOPPER COMPANY, OF NEW YORK, N. Y., A CORPORATION OF NEW JERSEY.

EQUALIZING MECHANISM.

No. 901,360.

Specification of Letters Patent. Patented Oct. 20, 1908.

Application filed January 14, 1905. Serial No. 241,135.

To all whom it may concern:

Be it known that I, FELIX MUELLER, a subject of the German Emperor, residing at New York, county of New York, and State 5 of New York, have invented certain new and useful Improvements in Equalizing Mechanisms, fully described and represented in the following specification and the accompanying drawings, forming a part of 10 the same.

This invention relates to certain improvements in apparatus for effecting equalized pressures.

In machines in which pressure is exerted 15 upon articles located between two pressure heads or between a pressure head and abutment, the pressure can of course be regulated by regulating the driving mechanism so long as the articles located between the pressure heads are constant in length. When, 20 however, it is desired to cause said mechanisms to operate upon articles differing in length, it is necessary of course either to provide a mechanism by which the pressure is relieved, or to in some way adjust the action 25 of the driving mechanism. Where, however, the machine is to operate rapidly upon articles varying or which may vary in length, it is not feasible to stop the machine 30 in order to adjust the driving mechanism, and devices of various kinds have been resorted to for relieving the pressure produced thereby. A common device for this purpose 35 consists in employing a spring located behind either the pressure head or the abutment, or both, which, after a given degree 40 of pressure has been applied, yields, thus permitting the driving mechanism to continue its stroke without damage to the article or mechanism. The force produced by a spring, however, increases rapidly with the increase of tension. For this reason, while such devices can be used satisfactorily in certain classes of machines, they are not 45 adapted for use in connection with machines where it is desired to produce substantially equal amounts of pressure upon articles varying in length without adjusting the driving mechanism.

50 In certain styles of presses, such, for instance, as presses for operating upon glass in molds and in the kinds of presses known as ore stamps, it has been customary to employ fluid containing cylinders provided 55 with relief valves which are operated when

the pressure developed rises to a certain degree. These devices have also been used in capping machines of a type similar to presses where caps or heads are to be applied to receptacles of varying length. The 60 use also of spring controlled tripping devices has been suggested in connection with this latter class of machines, these tripping devices operating to relieve the force of the spring after the pressure developed has risen 65 to a certain predetermined degree. These devices, however, are more or less complicated and consequently are expensive to construct, and the spring controlled tripping devices have the further objection that they 70 act to entirely relieve the pressure when they are brought into operation, instead of maintaining it throughout the operation of the driving mechanism as it is frequently desirable to do.

75 The present invention has for its object to produce an improved mechanism for effecting equalized pressures on articles varying in length, the articles being located between pressure heads or a pressure head and abutment, either or both of which may be movable, and in which the operation of the pressure controlling devices depends upon a weight.

80 With this and other objects not specifically stated in view, the invention consists in certain constructions and in certain parts, improvements and combinations as will be hereinafter described and pointed out.

85 Referring to the accompanying drawings—Figure 1 represents in side elevation, partly in section, one form of machine embodying the invention, and Fig. 2 represents 90 a front elevation of the machine illustrated in Fig. 1.

95 The concrete embodiment of the invention which has been selected for the purposes of illustration, consists of a machine for capping receptacles, but it is to be understood that the invention is capable of use in many 100 other relations. In the particular machine selected to illustrate the invention, the operative parts of the machine are supported in a frame 1 which may be varied in its configuration, according to the character of the 105 machine in which the invention is embodied. A machine embodying the invention will include a pair of pressure heads, or a pressure head and an abutment, either or both of which may be movable. In the particular 110

construction shown, one of the pressure heads includes a table or support 2 which is carried in an arm or bracket 3 forming a part of the machine frame, said table or support having a stem 4 which enters the frame and being provided with a suitable receptacle supporting device 5. The co-operating pressure head, in the specific machine in which the invention is embodied, includes a head 6 which applies the cap. This cap applying head, when the invention is embodied in a capping machine, may be of any desired construction. As illustrated, this head operates not only to force the cap down upon the bottle, but also to bend the flange of the cap beneath the shoulder which surrounds the mouth of the bottle. The bending devices may be of any suitable character, a die being indicated at 7. The head may be mounted so as to receive movement in any desired manner. As illustrated, the frame is provided with a tubular bearing 8 which is suitably supported on the frame, and the stem 9 of the head slides in this bearing as the head is reciprocated.

The driving mechanism which operates the head, or heads, when both heads are movable, may be varied widely in construction, and will vary according to the type of machine in which the invention is embodied. In the construction shown, the driver consists of a shaft 10 and, while the connections between the driver and the head may be of any suitable character, in the construction shown, this shaft 10 is provided with two cranks 11 to each of which is secured a connecting rod 12. These connecting rods 12 are secured to a cross bar 13 which passes through the stem 9 of the head 6.

The pressure controlling mechanism depends on the action of a weight or its equivalent. While the means by which the weight, or its equivalent, controls the pressure to be exerted by the heads upon articles operated upon in the machine may be varied within wide limits, in the particular construction shown it is such as to permit the relative position of the heads and driver to be changed when a predetermined degree of pressure has been exerted on the article, the relative position of the heads with respect to each other remaining unchanged. The specific means by which this is accomplished may be of any suitable character.

In the particular construction shown, the driver which, as has been before pointed out, consists of the shaft 10, is mounted in a movable carrier, the movement of this carrier being controlled by the weight. While the particular construction of the carrier may also be varied, in the construction selected for illustration, the carrier consists of a drum, the heads 14 of this drum being provided with suitable bearings 15 in which the shaft 10 is mounted. The drum heads 14

are carried on a shaft 16 suitably supported in the frame, the drum heads being further connected by a cross rod 17, as usual in such constructions.

The weight employed may be variously arranged. In the particular construction shown, it consists of a plurality of bars 18, these bars being connected to strips 19. These strips are flexibly connected to the drums 14, as, for instance, by chains 20. The chains and weights are so arranged as to hold the carrier in such position to enable the pressure heads to operate properly on a bottle or other receptacle of the shortest length. In the particular construction shown, a stop is provided which determines this position of the carrier. While this stop may be of any suitable character, in the construction shown, it comprises a pair of arms 21, these arms being provided with bearings 22 which receive the shaft 10 between them when the carrier occupies the position referred to. These arms are or may be supported in any suitable manner, as, for instance, they may be attached to a cross bar 23 suitably connected to the frame of the machine.

The means for effecting the operation of the driver may be widely varied. As shown, the driver is provided with a gear 24 which meshes with a gear 25, said gear being loose on the shaft 16 and being rigidly connected to any suitable driving means, as, for instance, a pulley 26.

With the construction as described, if the shortest article on which the machine is designed to operate, be placed between the pressure heads and the shaft 10 be rotated, the head 6 will be reciprocated, the operations designed to be carried out by the machine being effected without bringing into action the power equalizing mechanism. If, however, a longer article is located between the heads, it will happen that after pressure sufficient to overcome the inertia of the weight has been exerted upon the article between the heads, the drum 14 will be caused to move, thus lifting the weight. This movement of the drum will continue until the cranks have passed the center, after which the carrier will move forward until the stops 21 come into action which will be at the time the weight has resumed its normal position. It will be seen that by this construction whether the article be longer or shorter, the force exerted upon it by the pressure heads will never exceed the force developed by the weight. Furthermore, inasmuch as the driving gear 24 is mounted upon the same center as the drum, the movement of the drum can take place without disturbing the driving relation between the gears 25 and 24. The mechanism is adapted for machines in which very rapid operations are to be carried out and the

pressure to be developed on articles of varying length can be calculated with extreme nicety.

While the particular construction shown is especially adapted for successfully carrying out the invention it is to be understood that the invention may be embodied in constructions which differ widely therefrom, and the invention is not, therefore, to be limited to the specific construction shown and described.

What is claimed is:—

1. The combination with a pair of pressure heads only one of which is movable, said heads being arranged to receive articles of varying length between them, of driving means for causing the heads to exert pressure on said articles, a weight, and means whereby after a predetermined amount of pressure is exerted by the heads on the article, any further force developed by the driving mechanism will be expended in raising the weight.

2. The combination with a pair of pressure heads only one of which is movable, said heads being arranged to receive articles of varying length between them, of a driver, rigid connections whereby the driver actuates the movable head to produce pressure on an article between the heads, and weight controlled means for permitting the relative position of the heads and driver to change when a predetermined degree of pressure has been exerted on the article, the relative position of the heads with respect to each other remaining unchanged.

3. The combination with a pair of pressure heads, one of which is movable, said heads being arranged to receive articles of varying length between them, a driver, rigid connections whereby the driver actuates the movable head to produce pressure on an article between the heads, and weight controlled means for permitting the driver to change its relative position with respect to the heads when a predetermined degree of pressure has been exerted on the article by the heads.

4. The combination with a pair of pressure heads only one of which is movable, said heads being arranged to receive articles of varying length between them, of a driving shaft, connections whereby the shaft actuates the movable head to produce pressure on an article between the heads, and weight controlled means for permitting the relative position of the heads and shaft to change when a predetermined degree of pressure has been exerted on the article, the relative position of heads with respect to each other remaining unchanged.

5. The combination with a pair of pressure heads, one of which is movable, said heads being arranged to receive articles of varying length between them, of a driving

shaft, connections whereby the shaft actuates the movable head to produce pressure on an article between the heads, and weight controlled means for permitting the shaft to change its position with respect to the heads 70 when a predetermined degree of pressure has been exerted on the article, the relative position of the heads with respect to each other remaining unchanged.

6. The combination with a pair of pressure heads constructed to receive articles of varying length between them, of a driver, connections whereby the driver causes the heads to exert pressure on said articles, a carrier in which the driver is mounted, a weight for 80 holding the carrier in position, and suitable connections between the weight and carrier whereby after the heads have exerted a predetermined pressure on the articles, the carrier and driver are moved away from the 85 heads against the force of the weight.

7. The combination with a pair of pressure heads arranged to receive articles of varying length between them one of said heads being movable, of a driving shaft, connections whereby the shaft actuates the movable head, a carrier in which the shaft is mounted, a weight, and suitable connections for holding the carrier in position, whereby when a force is exerted on the articles between the heads which tends to become greater than the force exerted by the weight, the carrier will move, whereby the heads are prevented from exerting more than a predetermined degree of pressure upon the article. 100

8. The combination with a pair of pressure heads, one of which is movable, said heads being arranged to receive articles of varying length between them, of a driving shaft, a carrier mounted to oscillate in which the shaft is mounted, means including a weight and suitable connections for maintaining the carrier in position, and operating connections between the shaft and the movable 110 head.

9. The combination with a pair of pressure heads arranged to receive articles of varying length between them, one of said heads being movable, of a driving shaft, operating connections between the shaft and the movable head, a carrier in which the shaft is mounted, said carrier being supported so as to oscillate about a center, a stop for positioning the carrier so that the heads may operate 120 upon the shortest article, and a weight for holding the carrier against the stop. 115

10. The combination with a pair of pressure heads arranged to receive articles of varying length between them, of a driving shaft, operating connections whereby the shaft causes the heads to exert pressure on an article between them, a drum in which the shaft is mounted, a stop for positioning the drum so that the heads will operate upon 130

the shortest article, and a weight connected to the drum for holding it against the stop.

11. The combination with a pair of pressure heads arranged to receive articles of varying length between them, of a driving shaft, a carrier supported to oscillate about a center in which said shaft is mounted, operating connections whereby the shaft causes the heads to exert pressure on the article, an operating gear mounted to rotate about a center on which the carrier oscillates, gearing between said gear and the operating shaft, a stop for positioning the carrier so that the heads will operate on the shortest article, and a weight for holding the carrier in operative relation with said stop.

12. In a capping machine, the combination with a pair of pressure heads, one of which operates to support the receptacle and the

other of which applies the cap thereto, means for effecting a relative movement between the heads, whereby the cap is applied to the receptacle, a carrier mounted to oscillate about a center, a driving shaft mounted in the carrier, operating connections between the shaft and one of the heads, a weight, and suitable connections for holding the carrier in position where the heads will operate upon the shortest receptacle, and suitable means for driving the shaft.

In testimony whereof, I have hereunto set my hand, in the presence of two subscribing witnesses.

FELIX MUELLER.
